UNITED STATES PATENT OFFICE

GEORGE W. SLYTER, OF TACOMA, WASHINGTON

DAVENPORT BED

Application filed September 9, 1925. Serial No. 55,215.

My invention relates to davenport beds, and particularly to a structure intended for incorporation into a davenport of the type employing a low seat having springs incorporated therein, either with or without loose cushions, and as exemplified in either the overstuffed type of furniture or the type having a finished back and arms, with upholstered or cushion seats.

10 An important object of the present invention is to provide a construction of davenport bed wherein the seat of the davenport is kept low, yet wherein springs of ample depth are provided for incorporation into the bed structure, including in the bed, when folded, sufficient room for a mattress.

15 A further object is the provision of such a structure in which the full effect of all of the springs may be secured when the piece is folded for use as a davenport; in other words, the provision of a structure wherein the seat is low and springy, to the full depth of all the springs. Associated with this it is an object in a davenport bed having such a low and 20 springy seat, to provide means whereby the bed when unfolded will lie at the proper height for beds.

25 A further object is the provision of a novel hinge structure, one which can be simply and cheaply constructed, and one permitting the ready shipment of the metal bed structure and hinge as a unit, and its ready incorporation into various forms of davenport framework.

30 A further object is the provision of novel means for the support of a bed section in a folding bed which is elevated when unfolded and dropped when folded, the said support being automatically engageable when the bed section is fully elevated and automatically disengageable at the commencement of the lowering operation.

35 A further object is the provision of a novel leg structure for employment in connection with such folding beds.

40 In general it is my object to simplify such devices to permit greater economies in their manufacture, shipment, and assembly, and to 45 produce a more comfortable piece of furni-

ture, which when folded will not suggest the possibility of its employment as a bed.

My invention comprises those novel parts and combinations thereof which are shown in the accompanying drawings, described in the 55 specification, and particularly defined by the claims terminating the same.

In the accompanying drawings I have shown my invention in the form which is now preferred by me.

50 Figure 1 is a transverse section through a davenport bed embodying my present invention, in folded position.

Figure 2 is a like view, the bed being shown in unfolded position.

55 Figure 3 is a plan view of such a davenport bed, unfolded.

Figure 4 is a diagrammatic view showing the end of such a bed structure, illustrating it at the commencement of the folding operation.

60 Figure 5 is a section on line 5—5 of Figure 3, and Figures 6 and 7 are, respectively, side elevation and axial section through a novel form of leg.

65 The present invention is best embodied in a two section bed, the inner or bed section 1 lying close to the floor when folded, and the outer or seat section 2 lying thereabove. When fully unfolded the two sections 1 and 2 70 lie substantially in the same plane. The section 1 is shown as comprising a frame 11 formed commonly of angle bars in the usual manner, having supported thereon coil springs 12 or like spring members, the tops 75

80 of which define the upper surface 13 of this section 1. The section 2 is likewise composed of a frame 21, shown as formed of angles in the usual manner and having springs 22 supported therein. Whereas the springs 12 are 85 shown as supported at one end upon metallic straps 10 extending between members of the frame 11, the springs 22, while supported from similar straps 20, are secured to these straps between their ends, the springs 22 being 90 preferably longer than the springs 12. Thus one end of the springs 22 define the plane of the bed, as at 23, this coinciding with the plane of the bed surface 13, while the other 95 end of the springs support a seat structure 100

24. It is, of course, an equivalent to employ two springs for each spring 22 shown. This seat structure, while shown as upholstered, may with equal facility be made merely as a support for the separate cushions usually employed in overstuffed furniture, to be laid upon this support.

The two sections 1 and 2 are pivotally connected by the edges which are forward when the bed is folded. For such hinge I prefer to employ a peculiar hinge structure, this comprising three plates arranged in adjoining planes, the plate 3 being adapted for attachment to the frame-work of the davenport, as, for example, the end frame 60, the plate 4 being adapted for attachment to the seat frame 21, and the plate 5 being adapted for attachment to the bed frame 11. The plates 4 and 5 are pivotally connected at one end of each, as indicated at 54. At its other end the plate 5 is secured to the forward edge of the frame 11, as indicated by the rivets 51. The plate 4 is longer than the plate 5 and is secured to the seat frame 21, as indicated by the rivets 42, between its ends, but preferably at substantially the same distance from the pivot 54 as the point of securing of the plate 5 to the frame 11. At its other end then, beyond the point of securing to the frame 21 from the pivot 54, the plate 4 is pivotally connected to the plate 3, as indicated by the pivot pin 53.

The removal of the common pivot 54 laterally from the planes of the frames 11 and 21 provides a large space between said frames when folded, in which space is contained the springs 12 and 22 and the mattress, while the placing of pivot 53 at the opposite side of the frames 11 and 21 drops the said frames lower in the casing when the bed is folded.

The plates 3, 4, and 5 are conveniently stamped of sheet iron or steel, and require little forming to adapt them for use. The manner of attaching the plate 3 to the end frame 60 may vary considerably. I have found it convenient to provide the plate 3 with a pair of notches or slots punched or cut from it, the slot 31 being above the slot 32, and the slot 32, if desired, being formed as an upwardly extending notch cut in the bottom edge of the plate 3. A plate 7 may be permanently attached to the end frame, as by wood screws or bolts, and this is formed with a hook 73 punched from the metal and directed upwardly to receive the notch 31. The plate 7 might also be provided with a like positioning member to be received in the slot 32, but I have found it most convenient to secure a bolt 72 in the end frame 60 in position to receive the slot 32, whereupon the bolt or a nut thereon can be drawn tight to clamp and hold the plate 3 to the end frame. By this means the device is readily secured within a prepared frame-work, and in furtherance of this end a side rail 61, constituting in effect a

part of the frame-work, may be secured to longitudinally directed flanges 36 bent from the plate 3, the plates being properly spaced and held in position in this manner, and the front rail 61 being conveniently held, yet not being in the way during the insertion and attachment of the bed structure.

When in folded position the frame 11 is suitably supported close to the floor, as by a longitudinal slat 62. When it is desired to unfold the bed, the seat or the seat frame 21 is engaged at its rear or inner edge, and is swung upward and outward on the pivot 53. In the folded position this pivot is above the plane of the frame 21, but when swung in opening the frame 21 is raised to a plane higher than the pivot 53. The frame 11 being connected to the frame 21 only by the pivot connection at 54, is not raised except as its forward edge swings upward with the swing of the pivot 54 about the pivot 53, until the pivoted edges of the frames 11 and 21 meet, as shown in the dotted line position in Figure 2, when the two sections are in the same plane, but tilted at an angle. This engagement of the two sections causes the section 11 to be swung upward as the section 21 is swung downward, and in the final position, unfolded, the two frames occupy substantially the same plane, both being horizontal. This position is shown in full lines in Figure 2.

Means must be provided for supporting the swinging edge of the frame 21 and the inner edge of the frame 11. The swinging edge of the frame 21 can conveniently be supported by any suitable type of folding leg, as indicated at 8, normally lying in the plane of the frame 21, but extensible to support the frame from the floor. The inner edge of the section 11, however, is preferably supported by automatically engageable, and automatically disengageable means, which as shown herein take the form of a plate 9 secured at its lower end to the end frame 60, as indicated by the screws or bolts 96, and having its upper end inclined toward the path of movement of the frame 11. The frame 11 is provided with a pin, as 19, which in swinging upward with the swing of the section 11 to its elevated position, will follow a prescribed circular path struck from the pivot 53. The plate 9 is arranged to project its upper end into the path of said pin. Therefore, as the section 11 swings upward, the pin 19 will engage the face of the plate 9, and this plate, being resilient, will yield to allow the pin to pass. At the uppermost position of the pin 19 the plate is provided with a slot or notch 91 facing rearwardly, and into this the pin 19 drops. Thus, while the bed is in the unfolded position as shown in full lines in Figure 2, the inner edge of the section 11 will be supported by engagement of the pin 19 with the notch 91.

In folding the action is not quite the same, for inasmuch as the inner end of the frame 11 is not permitted to swing downward on the pivot 53, the two frames will immediately separate at their adjoining edges, and 5 as seen in Figure 4 the frame 11 will be moved rearwardly as the frame 21 is swung upward. This continues until the pin 19 comes to the end of the slot 91 at the rear edge of the plate 9. This disengages the pin 10 from its slot and this edge of the frame 11 is then permitted to drop until it comes to rest on the slat 62. The frame 11 drops to the bottom of the davenport frame-work and the frame 21, swinging over, lies there- 15 above. The springs 22 of the section 2 rest upon the springs 12 of the section 1, except as they are spaced apart by a mattress M folding between them. The inner edge of the section 2 is unsupported when folded, 20 except by its springs resting on the springs of the section 1. Thus the seat of the davenport obtains the combined effect of the springs 12 and the full length of the springs 22.

The leg construction which I prefer to employ is best shown in Figures 7 and 8. It comprises a leg member 8, preferably pressed of fairly heavy sheet iron or steel to provide marginal flanges 80. These add 25 stiffness to the leg and in addition adapt it to be positioned about a cup-like hub 81 which is secured to the frame 21, as by the bolts 82, with the bottom of the cup spaced above the angle of the frame 21. Both the hub 81 and the leg 8 at its upper end have 30 apertures for the reception of a pivot pin 83, having heads on both ends. This pivot pin has interposed between it and the hub a spring or springs, shown herein as the 35 crossed flat springs 84. The pin might be extended through the angle of the frame 21 and have the spring secured on this extension, but in view of the cup-like character of the hub 81, and by the use of flat springs 40 84, they can be conveniently placed within this hub, thus avoiding the necessity of drilling the frame 21 for the pin 83, and covering the entire pivot so that bedding cannot catch thereon. In addition to the apertures for the pin 83, the leg is provided with 45 a boss 85 or like device pressed into the metal and adapted to coincide with indentations 86 in the hub, concentrically arranged about the pivot aperture, and shown as comprising 50 punched holes. By this means the leg can be definitely positioned in extended position by engagement of the boss 85 with the proper hole 86, and it can likewise be definitely positioned in the proper folded position by en- 55 gagement with another hole.

The entire hinge construction can be simply made of stampings, and is extremely simple to assemble. It provides a means whereby the entire metal work can be made up 60 in a single factory and shipped to manufac-

turers at various points, who can incorporate it into davenports upholstered in various types and according to the demands of their particular trade. The bed when unfolded is of the standard height for beds, yet the 70 seat when folded is as low as is required of davenport seats, and is provided with at least as great resilience as is ordinarily provided in such davenports. The folding and unfolding operation is extremely simple, unfolding requiring merely the swinging over of the seat section 2 and the unfolding of the legs 8, and the folding requiring merely the reverse operation, the folding of the legs and the swinging over of the seat 2. No attention need be paid to the bed section 1 which 75 is automatically brought into elevated position and locked there and which is automatically unlocked.

The seat, while low, nevertheless provides 80 space beneath it for the storage of a mattress, as is desirable in such devices, and the use of this mattress does not affect the resili- 85 ent character of the seat, but in effect serves to form a medium of communication between the springs in the bed section 1 and in the seat section 2, so that if the springs in the two sections do not exactly coincide when folded, 90 their full effect will be transmitted from one section to the other through the mattress M. 95

What I claim as my invention is:

1. In a davenport bed, the combination with a bed frame and a seat frame pivotally supported at its forward edge and positioned above said bed frame when folded, the forward edges of said frames being pivotally connected, the pivotal connection lying substantially midway between the planes of the frames when folded, whereby their forward edges will substantially coincide as the seat frame is swung towards unfolded position, of means for supporting the inner edge of said bed frame in upraised position when unfolded, said means comprising a longitudinally-extending pin carried by the inner edge 100 of the bed frame, and a resilient support extending in the path of said pin and yieldable lengthwise of the bed, said support having a rearwardly directed notch for the reception of the pin, when said frame section is 105 raised.

2. In combination with a folding bed section and means for elevating the same, a pin carried by said bed section and extending longitudinally, a plate having its upper end inclined into the upward path of said pin, and including such path of movement between its edges, said plate also having a rearwardly opening notch positioned to receive said pin as the bed section reaches its elevated position, the plate being yieldable to permit engagement of the pin and notch. 115

3. In combination with a folding bed section and means for elevating the same, a pin carried by said bed section and extending lon- 120

gitudinally, a plate having its upper end inclined into the upward path of said pin, and including such path of movement between its edges, said plate also having a rearwardly opening notch positioned to receive said pin as the bed section reaches its elevated position, the plate being yieldable to permit engagement of the pin and notch, the bed section elevating means being disposed to move said section bodily rearward upon the commencement of the lowering movement, and said pin and notch being so disposed and arranged, relative to the said elevating means, as to be disengaged by such bodily movement of the bed section, to permit lowering thereof.

4. In a davenport bed, a plurality of bed frames and means pivoting them together by their longer edges, a pivot for the same edge of the outer frame section located below the first named pivots, end projecting pins carried adjacent the inner edge of the inner bed section, and supporting members yieldable lengthwise of the bed sections and positioned for engagement by said pins as the bed is opened, said supporting members having rearwardly opening slots adapted to receive said pins and to release the pins when said inner bed section is moved rearwardly in folding the bed.

20 5. Signed at Tacoma, Pierce County, Washington, this 2nd day of September, 1925.

GEORGE W. SLYTER.
